DEFROSTER

John A. Shrader, Kitchel, Ind.

Application July 21, 1934, Serial No. 736,408

1 Claim. (Cl. 62—4)

This invention relates to a defroster for a refrigerator or similar device of the character having a cooling or freezing unit and has for the primary object the provision of means for directing a blast of air onto the cooling or freezing unit at any selected period of time to bring about a thorough or rapid defrosting for removal of the snow or ice on the cooling or freezing unit and which may take place while the refrigerator or similar device is closed to the atmosphere which permits the refrigerator to remain at a low or lower temperature than heretofore accomplished through the ordinary way of defrosting.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a fragmentary view showing my invention applied to a cooling or freezing unit of a refrigerator or similar device.

Figure 2 is a diagrammatical view illustrating the wiring diagram with my invention electrically connected thereto.

Referring in detail to the drawing, the numeral 1 indicates a cooling or freezing unit of the conventional construction adapted for cooling a refrigerator or like device 2. To maintain the unit 1 at its highest point of efficiency it is necessary to defrost or remove from the unit the accumulation of snow or ice which is usually accomplished by rendering the device inoperative for a period of time to permit the snow and ice to melt from said unit. Usually the defrosting operation requires a number of hours in which time the interior of the refrigerator or like device rises in temperature and to reduce the length of time to defrost the unit and to maintain the refrigerator at a comparatively low temperature my invention is employed which consists of a medium 3 to direct a blast of air onto the cooling or freezing unit during the time of defrosting so that the ice and snow will more rapidly melt and the blast of air passing over the melting snow will be lowered in temperature consequently aiding in maintaining the refrigerator at a compara-

tively low temperature. The medium 3 is in the form of an electric motor 4 having secured to the armature shaft thereof a fan 5. The motor 4 may be located within any desired place in the refrigerator so that the fan 5 when in operation can direct air against the freezing or cooling unit 1. Figure 2 shows the wiring 6 of an electrically actuated circuit for the unit 1 and which circuit is opened and closed by a temperature control 7. The temperature control is in the nature of a bellows-like member which is expanded or contracted by temperature conditions. The electric motor 4 is connected to the electric circuit 6 by conductors 8, 9 and 10. The conductors 8 and 9 are separated by spaced contacts 11. 15 Pivoted to the top of the temperature control 7 there is one end of a lever 12, that is centrally pivoted to a supporting standard 13. The outer or free end of the lever has arranged therearound but insulated therefrom a U-shaped contact plate 14. Subjacent the contact plate 14 there is positioned a pair of spaced contacts 15 each connected to one of the pair of main circuit wires 6 leading to the compressor motor for the unit 1. The contact plate 14 is movable by the lever 12 20 to bridge the spaced contacts 11 to direct current from the main circuit to the fan motor 4 and break the connection between the contacts 15 to shut off current from said main circuit to the compressor motor for unit 1, or vice versa, in accordance with the expansion or contraction of the control element 7. Thus it will be seen that the electric motor 4 is set in operation when the motor of the refrigerant unit is stopped. This arrangement or means for directing air onto the 25 cooling coil when the compressor is idle will materially aid in preventing the accumulation of frost and snow thereon thereby practically keeping the cooling unit in a defrosted condition over a long 30 period of time.

Having described the invention, I claim:

The combination with a refrigerating system including its evaporator, compressor and driving motor therefor, of an independent motor driven fan for causing a flow of air through the refrigerator evaporator, and a thermostat controlling the refrigerating system compressor motor and fan driving motor for alternate operations.

JOHN A. SHRADER.
